SCREEN-CLOSURE CONSTRUCTION

Application filed September 20, 1928. Serial No. 307,206.

This invention relates to new and useful improvements in screen closure construction and to a novel method of manufacturing the screen closure members and the molding strips 5 therefor.

The present invention is an improvement upon the construction disclosed in my copending application Serial No. 262,383, filed March 17, 1928.

10 In the above-mentioned pending application, the inner edges of the frame members are rabbeted to receive the edges of the screen cloth. The shoulders of the rabbets are so undercut as to continue the surface of the bottom or of the face of the rabbet to which the screen is applied a suitable distance beyond said shoulder. This arrangement eliminates the necessity of trimming the screen to exact dimensions and permits the location of the 15 surplus screen beyond the molding strip. A

groove is cut longitudinally in the rabbet at right angles to the plane thereof for enabling the folding of the screen within said groove throughout the entire length of said rabbet.

20 Thus all pulling strain to which the edge of the screen may be subjected, instead of being resisted at spaced points of the screen edge (as is done in the ordinary screen construction 25 wherein tacks are used to secure the screen in

30 position) is transmitted to the entire edge of the screen by virtue of the fact that the folded portion is disposed in said groove substantially at right angles to the plane of the screen. A molding strip having a flat bottom 35 is secured in position in the rabbet and holds the wire cloth therein.

The present invention contemplates the use 40 of a molding strip having a downwardly projecting longitudinally disposed rib or tongue 45 which fits into the groove of the seat or rabbet and clamps the wire cloth in position therein. This not only insures more secure anchoring of the wire cloth but also serves to tension 50 said wire cloth and to hold it taut throughout the entire length of the rabbet.

Furthermore, according to my invention, 55 the molding strip can be made from the frame stock by the same operation that forms the rabbet in the latter, thereby eliminating waste- 60 age of the material and effecting saving of the

cost of the stock from which the molding strip has been heretofore made. This molding strip can be given proper contour by the use of appropriate mill cutters during the face cutting operation. 55

With these and other objects in view, my invention consists in certain novel features of construction and arrangement of parts, hereinafter more fully described and claimed, and illustrated in the accompanying drawings, in 60 which—

Figure 1 shows a cross section of a stock piece from which the frame is made.

Figure 2 shows the first step of the operation, namely, finishing one edge of said stock 65 to form the tongue of the molding strip.

Figure 3 illustrates the second step, namely, 70 that of cutting a vertical groove and simultaneously forming the contour of the molding strip.

Figure 4 shows the third step, namely, 75 forming the rabbet and simultaneously severing the molding strip and forming the horizontal groove in the shoulder of the rabbet.

Figure 5 shows the molding strip in position in the rabbet with the wire cloth clamped therebetween. 80

In practicing my present invention, I take a piece of frame stock, such as indicated at 10, and trim one edge thereof to provide a longitudinally disposed outwardly projecting tongue or rib 12. This rib is spaced a suitable distance from the upper face of the stock and extends throughout the entire length thereof. The upper face of the stock 85 is then operated upon, preferably by a mill cutter, so as to form a vertically and longitudinally disposed groove 14 and at the same time provide a proper finish for the upper face of the outer portion 15. The depth of groove 14 is considerably greater than the depth of the proposed rabbet as indicated at 14^a. By using an appropriate mill cutter, the upper face of the outer portion 15 can be given the proper contour desired in the finished molding strip. 90

The edge of the stock piece is now cut longitudinally throughout its entire length at right angles to the first cut at a point coincident with the depth of the rabbet, as indi- 100

cated at 16. The depth of this cut is greater than the width of the proposed rabbet thereby providing a longitudinally disposed groove 16^a which extends under the shoulder 17 and is in the same plane with the face 18 of a rabbet 19, thus formed.

In this manner, the portion 15 is severed from the stock piece 10, thereby forming a molding strip 20 and the rabbet 19. The planes of the faces forming the rabbet are extended inwardly beyond said rabbet.

When the screen is placed in position, groove 16^a receives the edge portion of the screen. The molding strip 20, when assembled on the frame, occupies a position which is displaced a quarter turn relative to the position formerly occupied by said strip when an integral part of the stock piece, thereby bringing the tongue 12 into the groove 14^a as shown in Figure 5. The tongue 12, upon entering groove 14^a, forces portion of the screen into said groove, as indicated at 21, and clamps said portion in said groove. Thus the screen is properly tensioned and is securely anchored in position on the frame by the interlocking engagement of tongue 12 with groove 14^a. The molding strip is then secured in position by nails 22.

Preferably the distance between the tongue 12 and the face of the strip 20, indicated at X, is substantially equal to or less than the distance between the edge of the rabbet and the groove 14^a as indicated at Y, so that when strip 20 is placed in position, its outer edge 35 does not project beyond the edge of the rabbet. Similarly the width of the strip, exclusive of the tongue, as indicated at Z, is substantially equal to, or slightly less than, the height of the depth of the rabbet as indicated at 31, whereby said strip when in position is substantially flush with or slightly below the face of the frame.

The thickness of tongue 14 is less than the width of groove 14^a to allow for the wire cloth positioned in the latter and to enable ready assembling of the strip. The tongue and groove anchoring of the wire cloth produces a safe and uniform tensioning of the wire fabric and serves to hold the latter securely in place. In this manner the wire cloth is reinforced as any sudden impacts, to which the wire cloth may be subjected, instead of being resisted at spaced points, as heretofore, are absorbed by the entire length 55 or width of the wire cloth.

My novel method of manufacturing the frame or stile stock, and the molding strips therefor, utilizes the wood heretofore wasted during rabbeting operations, and eliminates the cost of manufacturing the molding strips, as the latter are made by the same operations which form the rabbets in the stock. Thus, by the use of my method, a great saving is effected in labor and material, enabling the

manufacturing of screen closure members in an economical manner.

I am aware that various minor changes could be made in the manufacture of my improved screen closure stock, and I contemplate such changes as fall within the scope of my invention.

I claim:

1. The method of manufacturing screen closure stock consisting in cutting one edge of a screen stock to form a longitudinally disposed tongue, then grooving longitudinally one face of said stock a suitable distance from the edge thereof, then grooving said edge longitudinally at right angle to the first groove, said grooves intersecting each other, thereby severing a molding strip and simultaneously forming a rabbet in said stock for receiving said strip, one of said grooves being adapted to receive the tongue of said strip.

2. The method of manufacturing screen closure stock consisting in grooving longitudinally one face of a stock piece a suitable distance from the edge thereof, then grooving said edge longitudinally at right angle to the first groove, said grooves intersecting each other and being of greater depths than the faces of the rabbet, thus formed, thereby providing countersunk grooves for receiving portions of a wire cloth, said rabbet being adapted to receive a molding strip having a longitudinally disposed tongue, one of said grooves being adapted to receive said tongue when said strip occupies position in said rabbet.

3. The method of manufacturing screen closure stock consisting in trimming one edge of a stock to form thereon a longitudinally disposed tongue, then grooving longitudinally one face of said stock a suitable distance from the edge thereof, then grooving said edge longitudinally at right angle to the first groove, said grooves intersecting each other to form a rabbet and the detached portion forming a moulding strip, said grooves being of greater depths than the faces of said rabbet to provide countersunk grooves for receiving portions of a wire cloth, and placing a molding strip in said rabbet with the longitudinally disposed tongue inserted in one of said grooves thereby clamping said wire cloth in position.

4. The method of manufacturing screen closure stock consisting in trimming one edge of a stock piece to form a longitudinally disposed tongue spaced a suitable distance from the face thereof, then grooving longitudinally the face of said stock a suitable distance from the edge thereof, and then grooving said edge longitudinally a suitable distance below said tongue and at right angles to the first groove, said grooves intersecting each other thereby severing said tongue portion from said stock and providing a molding

strip, forming a rabbet in said stock piece, the grooves being of greater depths than the faces of said rabbet to form countersunk grooves for receiving portions of a wire cloth, 5 one of said grooves being adapted to receive the tongue of said molding strip thereby clamping the wire cloth therein.

5. The method of manufacturing screen closure stock consisting in finishing one edge 10 of a stock piece to provide a longitudinally disposed tongue spaced suitable distances from the faces thereof, then grooving longitudinally one face of said stock and the edge thereof at right angles to each other, said 15 grooves intersecting each other thereby severing said tongue portion from said stock and providing a molding strip for the rabbet thus formed, one of said grooves being adapted to receive the tongue of said molding strip 20 for clamping the wire cloth therein.

In testimony whereof I hereunto affix my signature this 12th day of September, 1928.
